CLAIM

The ornamental design for a sectional sofa combination, as shown and described.

DESCRIPTION

FIG. 1 is a front, left, top perspective view of a first component of a sectional sofa combination, shown separately for ease of illustration;

FIG. 2 is a rear, right, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, left, top perspective view of a second component of the sectional sofa combination, shown separately for ease of illustration;

FIG. 10 is a rear, right, bottom perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a front, left, top perspective view of a third component of the sectional sofa combination, shown separately for ease of illustration;

FIG. 18 is a rear, right, bottom perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof;

FIG. 25 is a perspective view of the first configuration, consisting of two first components and two second components assembled together;

FIG. 26 is a perspective view of the second configuration, consisting of four first components, two second components and two third components assembled together;

(Continued)

FIG. 27 is a perspective view of the third configuration, consisting of three first components, two second components and the third component assembled together; and, FIG. 28 is a perspective view of the fourth configuration, consisting of two first components and two second components assembled together.
